THERMOSTATIC CONTROL FOR ELECTRICAL HEATING ELEMENTS

George W. Crise, Columbus, Ohio

Application July 23, 1947, Serial No. 762,936

8 Claims. (Cl. 219—20)

1

The present invention relates to thermostatic switches, and has particular reference to an improved thermostatic control for electrical heating elements and the like. In its more specific aspects, the invention deals with a thermostatic switch control adapted for use in conjunction with electrical bed warmers and blankets.

The principal object of the present invention is to provide a simple and mechanically efficient thermostat for controlling the operating temperature of an electric bed warmer or blanket, which functions in a safe and efficient manner to limit the maximum temperature which the heating element of the warmer may attain.

It is another object of this invention to provide a thermostatic switch for the heating element of a bed warmer which insures an even and uniform temperature throughout the bed warmer in accordance with the desires of the user, and which further provides a simplified manually adjustable control for varying the operating temperatures of the bed warmer.

It is a further object of this invention to provide a thermostatic switch of the character described which comprises but few and relatively simple component parts which may be assembled within a relatively small and compact unit, and as such, occupies but little space, and may be positioned remotely of the bed warmer or blanket, thereby eliminating undesirable and uncomfortable bulges within the associated bed warmer.

For a further and more detailed understanding of the present invention and the additional objects and advantages thereof, reference is made to the following description and the accompanying drawing, which discloses in diagrammatic form the electrical circuit and component parts utilized in the present invention.

Referring now to the drawing, the present invention makes use of a pair of independently supported bimetallic arms 5 and 6, with the arm 5 being rigidly attached at its inner end to a stationary insulated support 7, and the arm 6 being rigidly secured to a pivotally mounted insulated support 8. Both of the arms 5 and 6 are positioned upon their respective supports so as to deflect downwardly, as indicated by dotted lines in the drawing, in response to the application of heat thereto, it being noted that both of the arms will deflect in the same general direction. Carried at the outer end of each of the arms 5 and 6 are a pair of relatively engageable circuit contact points 9 and 10. The arms 5 and 6 and their associated contacts are normally positioned so as to maintain the contacts in engagement with one

2

another, and in the event the arms 5 and 6 are thermally deflected in an even and uniform manner, and to the same extent, the contacts 9 and 10 will remain in sliding but continuous engagement with one another.

Disposed in proximity to the deflectable arms is an insulated circuit terminal support 11 provided with circuit terminals 12, 13 and 14. Connected with the circuit terminals 13 and 14 are lead wires 15 and 16 respectively, which serve to furnish current for the switch and its associated lead. Electrically connected with the terminals 12 and 13 is a main heating element 17 which is normally positioned within the bed warmer or blanket, and which comprises a coil of resistance wire, such as copper, or alloys thereof, and which is of relatively high resistance, with its resistance increasing as the temperature rises within the coils. Leading from the terminal 14 is a lead wire 18 which is electrically joined with a low resistance heating coil 19 wound about the bimetallic arm 6. The opposite end of the low resistance coil 19 is electrically joined through the arm 6 to its associated contact point 9. Upon engagement of the contact points 9 and 10, the circuit continues through the contact 10 and its associated arm 5 to a second lead wire 20 joining the inner end of the bimetallic arm 5 with the circuit terminal 12. In this manner, it will be seen that current is furnished the main heating element 17, upon engagement of the contact points 9 and 10, by way of the two bimetallic arms 5 and 6. Wound about the bimetallic arm 5 is a relatively high resistance heating coil 21 which is connected at its respective ends to the bimetallic arm 5 and to the circuit terminal 13 by means of a third lead wire 22. Thus it will be seen that both the main heating element 17 and the relatively high resistance heating coil 21 are connected together in parallel, whereby both operate from substantially the same voltage. Preferably, the low resistance heating coil 19 is formed from any suitable alloy having constant resistance characteristics or a negative coefficient of resistance, whereby the resistance of the coil remains substantially unchanged with an increase or decrease in temperature. One suitable alloy answering these specifications is known commercially as manganin, and is an alloy of copper, nickel and manganese. The relatively high resistance heating coil 21 may be formed from any suitable high resistance alloy, such as Nichrome or the like, and need not possess a substantially constant resistance or coefficient of resistance. As before stated, the main

heating element 17 of the bed warmer is usually formed from copper, or an alloy containing a considerable percentage of copper, and is subject to an increase in resistance with an increase in temperature.

As current is supplied to the switch by way of supply conduits 15 and 16, current will pass from conduit 15 through terminal 14, lead wire 18 and into the relatively low resistance heating coil 19 which, upon engagement of the contacts 9 and 10, will be warmed and will be maintained at a substantially constant temperature, and by thermal conductivity, its associated bimetallic arm 6 will be warmed and deflected downwardly, as indicated by broken lines in the drawing. At the same time, current will pass from the coil 19 through the contacts 9 and 10, and through the bimetallic arm 5, by way of the second lead wire 20, to the circuit terminal 12 and thence to the main heating coil 17, whereupon the circuit is completed with the supply conduit 16 thereby heating the main heating coil 17. As before stated, the relatively high resistance heating coil 21 is connected in parallel with the main heating element 17, and thereby receives the same operating voltage, and will be warmed by the same voltage as the main heating element 17. In this manner, heat is supplied to the bimetallic arm 5 causing the same to deflect downwardly, as is also indicated by dotted lines in the drawing. Initially, the amount of heat supplied by the heating coils 19 and 21 will be substantially the same, with the two bimetallic arms deflecting downwardly at a uniform rate, and to the same extent, but as the main heating element 17 is warmed, its resistance will be increased and will therefore pass a decreased operating current, thus diminishing the operating current within the relatively low resistance coil 19.

At the same time, the high resistance coil 21, being in parallel with the main heating element, will receive the same voltage as the heating element, and consequently will become heated to a slightly greater extent due to line voltage increase resulting from load decrease thereby causing the bimetallic arm 5 to deflect a slightly greater distance downward while at the same time the reduced current being drawn through the series heater coil 19 will permit it to cool and deflect upwardly breaking contacts 9 and 10. Upon the opening of the contacts 9 and 10, the entire operating circuit will be opened, thereby allowing the heating coils 19 and 21 to cool and return to their normal positions, whereupon the contact points 9 and 10 will again become engaged to repeat the cycle of operation just described. It will be understood, that the variation in the extent of deflection of the two bimetallic arms 5 and 6 is accomplished wholly through the difference in temperature of the two heating coils 19 and 21, the same remaining substantially constant until an increase in temperature is accomplished within the main heating element 17, whereupon its resistance increases, causing a slight increase in the heat supply of the heating coil 21 and a substantial decrease in the heat supply of coil 19.

To vary the tension between the contact points 9 and 10 independently of the thermal deflection of the arms 5 and 6, a third bimetallic arm 23 is rigidly secured at one of its ends to the opposite side of the pivotally mounted insulated support 8. The opposite end of this bimetallic arm is carried by and subjected to the movement of a manually controlled and pivotally mounted lever

24. The bimetallic arm 23 is thermally insulated from the heating coils 19 and 21 by means of a barrier wall 25 formed from any suitable thermally insulating material which will serve to prevent the passage of heat by convection from the heating coils to the bimetallic arm 23, whereby the same will act only in response to temperature variations within the atmosphere surrounding the switch. The arm 23 is positioned so as to deflect downwardly, as indicated by broken lines in the drawings, in response to an increase in temperature of the surrounding atmosphere.

Thus, as the temperature of the surrounding atmosphere increases, the arm 23 will be deflected downwardly and will cause the pivotally mounted support 8 to rock in a limited clockwise motion, as viewed in the drawing. This rocking motion within the support 8 will, in turn, tend to lift the bimetallic arm 6 upwardly, and will tend to decrease the tension between the contact points 9 and 10, thereby decreasing the amount of relative deflection between the arms 5 and 6 necessary to open the power circuit of the switch. In addition to the thermostatic control provided by the independent bimetallic arm 23, the tension between the two contact points 9 and 10 may be varied by the movement of the manually adjustable lever 24, and as the same is rotated or pivoted in a substantially counterclockwise manner, the tension between the points will be decreased causing an opening of the operating circuit at a relatively lower temperature within the heating element 17.

35 To prevent overheating within the heating element 17, and to limit the maximum operating temperature thereof, a stop 26 is positioned adjacent the upper arm of the pivotally mounted support 8, so as to prevent counterclockwise movement thereof tending to increase the initial tension between the contact points 9 and 10 and limiting the clockwise movement of the manually operable lever 24 to a desired maximum safe operating temperature within the heating element. Thus it will be seen that by establishing an initial resilient tension within the deflectable arms 5 and 6, as the same are arranged as shown in the drawing, this tension may be decreased by action of the bimetallic arm 23 acting in response to a temperature increase of the surrounding room atmosphere. In addition, the manually adjustable lever 24 may be adjusted to control the degree of tension within the two arms 5 and 6 in accordance with the desires for a predetermined maximum temperature within the main heating element 17, thereby controlling the maximum temperature which the heating element 17 will reach before the opening of the circuit contacts 9 and 10.

60 In view of the foregoing, it will be seen that the present invention provides both a highly useful and mechanically efficient thermostatic switch for controlling the operation of an electrical heating element, with particular reference to electrical heating elements of the type utilized in bed warmers or electrically heated blankets. The switch operates efficiently to control both the operating temperature of the heating element, and to control the maximum safe temperature 65 which the element may attain. An important advantage of such switches resides in the fact that the same may be positioned remotely of the main heating element 17 to eliminate undesirable and uncomfortable bulges within the associated 70 bed warmer or blanket which would be necessary

tated if direct thermal contact thermostats were scattered through the warmer to limit its temperature.

I claim:

1. A thermostatic control for electrical heating elements of variable resistance comprising a first thermally deflectable member, a second thermally deflectable member arranged to move in the same general direction as said first member in response to increased temperature conditions, relatively engageable circuit contacts carried by said members in normally closed relation, said contacts being directly connected in series with an electrical heating element, a low resistance heating coil carried by one of said members and connected in series upon closure of said contacts with the heating element, and a high resistance heating coil carried by said second member and electrically connected in parallel upon closure of said contacts with the heating element, whereby variations in operating current of the heating element will result in variation in the magnitude of heat energy transmitted by said heating coils to each of said members to cause an uneven thermal deflection thereof and disengagement of said circuit contacts.

2. A thermostatic control for variable resistance electrical heating elements having an operating circuit, comprising a pair of independently supported cooperative thermally deflectable members connected in series with the heating element and arranged to deflect in the same general direction in response to increased temperature conditions, a pair of relatively engageable circuit contacts electrically connected with and carried by said members for directly controlling the energization of the heating element, said thermally deflectable members being arranged so as to normally maintain said contacts in engagement in response to substantially equal temperature conditions at the respective members, a high resistance heater coil carried by one of said members and connected in parallel with the heating element for supplying heat to its associated member, and a low resistance heater coil carried by the other of said members and connected in series with the heating element, whereby a variation in resistance within the heating element causes a variation in the magnitude of heat energy within said heater coils and an uneven thermal deflection of said members to disengage said contacts.

3. A thermostatic control for variable resistance electrical heating elements having an operating circuit, comprising a first bimetallic arm arranged for thermal deflection in a given plane, a second independently supported bimetallic arm arranged for thermal deflection in the same general plane as said first arm and in the same general direction in response to increased temperature conditions, said arms being electrically connected in series with the heating element, a pair of relatively engageable circuit contacts carried by said arms in normally engaged relation, said contacts when engaged serving to close the operating circuit of the heating element and when disengaged to open the operating circuit of the heating element, a substantially constant resistance heating coil carried by said first arm in series with the heating element and operable upon engagement of said contacts to heat said first arm, and a high resistance heating coil carried by said second arm in parallel with the heating element and operable upon engagement of said contacts to heat said second arm.

4. A thermostatic control for electrical loads of

variable resistance, comprising a pair of relatively engageable overlapping circuit contacts connected in series with the load and operable upon engagement to close the operating circuit of the load, a first bimetal arm supporting one of said contacts and arranged to deflect in a direction to open said contacts in response to increased temperature conditions, a relatively high resistance heating coil carried by said first arm and connected in parallel with the load and operable upon engagement of said contacts to heat said first arm, a second bimetal arm supporting the other of said contacts and arranged to deflect in a direction to close said contacts in response to increased temperature conditions, and a relatively low resistance heating coil carried by said second arm and connected in series with the load and operable upon engagement of said contacts to heat said second arm, both of said heating coils being arranged to be deenergized upon disengagement of said contacts.

5. A thermostatic control for electrical loads of variable resistance, comprising a pair of relatively engageable overlapping circuit contacts connected in series with the load and operable upon engagement to close the operating circuit of the load, a first bimetal arm supporting one of said contacts and arranged to deflect in a direction to open said contacts in response to increased temperature conditions, a relatively high resistance heating coil carried by said first arm and connected in parallel with the load and operable upon engagement of said contacts to heat said first arm, a second bimetal arm supporting the other of said contacts and arranged to deflect in a direction to close said contacts in response to increased temperature conditions, a relatively low resistance heating coil carried by said second arm and connected in series with the load and operable upon engagement of said contacts to heat said second arm, both of said heating coils being arranged to be deenergized upon disengagement of said contacts, and a third bimetal arm linked to one of said first-named bimetal arms and thermally insulated from said heating coils for moving one of said first-named arms independently of thermal deflection within said first and second arms.

6. A thermostatic control for variable resistance heating elements having an operating circuit, comprising a first bimetallic arm having a rigidly supported end and a free end, a second bimetallic arm having a rigidly supported end and a free end arranged to deflect in the path of the free end of said first arm in response to variations in temperature conditions, a pair of relatively engageable circuit contacts carried by the free ends of said arms and connected in series with the heating element, a relatively low resistance heating coil carried in close thermal relation to said second arm and electrically connected in series with the heating element, said low resistance heating coil being operable upon energization to cause said second arm to move in a direction to close said contacts, and a relatively high resistance heating coil carried in close thermal relation with said first arm and electrically connected in parallel with the heating element, said high resistance heating coil being operable upon energization to cause said first arm to move in a direction to open said contacts, both of said heating coils being arranged so as to become deenergized upon disengagement of said contacts.

7. In a thermostatic control for variable resistance electrical heating elements having an

operating circuit; a pair of unconnected thermally deflectable members arranged to move in the same general direction in response to increased temperature conditions; a pair of relatively engageable circuit contacts carried by said members and directly connected in series with the electrical heating element, said contacts when engaged serving to close the operating circuit of said heating element and when disengaged to open said circuit; a first resistance carried on one of said members and connected in series through said contacts with the heating element for heating one of said members in direct proportion to the amount of current passing to the heating element; and a second relatively higher resistance carried on the other of said members and connected in parallel through said contacts with the heating element for heating the other of said members in proportion to the voltage across said heating element.

8. In a thermostatic control for variable resistance electrical heating elements having an operating circuit; a pair of thermally deflectable members arranged to deflect in the same general direction in response to temperature increases and having a pair of normally engaged circuit contacts connected in series with the electrical heating element for directly controlling the

energization thereof; means disposed in thermal proximity to one of said arms and connected in series with said heating element through said contacts for supplying heat to said one of said arms in direct proportion to the amount of current passing to said heating element upon engagement of said contacts; and means disposed in thermal proximity to the other of said arms and connected in parallel with said heating element through said contacts for supplying heat to said other of said arms in direct proportion to the voltage across said heating element upon engagement of said contacts.
